UNITED STATES PATENT OFFICE

LA. FAYETTE D. VORCE, OF MONTCLAIR, NEW JERSEY, ASSIGNOR TO WESTVACO CHLORINE PRODUCTS, INC., OF NEW YORK, N. Y., A CORPORATION OF WEST VIRGINIA

ELECTROLYTIC CELL

Application filed September 14, 1929. Serial No. 392,627.

This invention relates to electrolytic cells; and it comprises an improvement in a type of cell used in making soda and chlorin and having interior anodes in a chamber formed by a metal cathode carrying a diaphragm and contained in a casing forming a cathode chamber, said improvement comprising a two part cover member fitting inside the top edges of the casing, with an inner or central part 5 of said member supporting the anodes and an outer or peripheral part being attached to the cathode, the weight of the cathode, diaphragm, anodes and cover resting on the bottom of the cell and a gas-tight seal of the 10 cover member with the casing being secured by a recessed plastic joint; all as more fully hereinafter set forth and as claimed.

Cells of the so-called cylindrical type are largely used in the electrolysis of salt solution to produce soda and chlorin. Cell units 20 of this type have a round or rectangular cathode of punched or perforated steel; this cathode carrying a diaphragm, usually asbestos. The cathode is mounted within a 25 steel casing defining a cathode chamber, while the anode chamber containing the anolyte, is within and defined by the diaphragm and cathode. At the top, the cathode compartment is closed by an annular top 30 member resting on and supported by a flange of the casing. The anode rods depend from and are carried by a cover resting on this top member. Thus the weight of the anode, cathode and anolyte is carried on the top 35 flange of the casing. This has certain mechanical and operating disadvantages.

It is the purpose of the present invention to simplify and cheapen this construction and produce a stronger and mechanically better 40 structure. Certain advantages in operation are also obtained. In the present invention I employ the usual outer casing and contained shell of perforated sheet metal acting as cathode and carrying a diaphragm, the 45 shell and casing defining a cathode chamber between them and the anode chamber being within the diaphragm cathode shell. But instead of suspending the interior parts of the cell from an annular flange on the top of 50 the casing, the weight of these elements rests on the bottom of the casing. In practice I form a bottom for the cathode shell by a base member of concrete while I provide the top of the casing with a two-part cover member, also of concrete or other suitable insulating 55 material fitting inside the top edges of the casing. The cover member comprises both a cathode ring and an anode ring and is provided with a recessed flange extending nearly to the casing, with a plastic "mastic" composition within the recess making a gas tight junction with the casing. The weight of the anode and the cover member instead of resting upon the top of the outer casing is supported by the cathode shell whose concrete 60 bottom is upon the bottom of the cell. The arrangement of the cell elements as above outlined constitutes a simplified construction lowering the expense of installation, lessening the maintenance requirements and improving the process of operation.

In the accompanying illustration I have shown, more or less diagrammatically, an embodiment of the present invention. In this showing the view is a central vertical section 75 of a complete cell.

As shown element 1 is a tanklike casing of sheet metal, open at the top and having a bottom 2. This casing may be round or rectangular but is shown as circular. Within the casing is a base plate 3 which is best made of concrete material and carries a vertical shell 4 of perforated or punched metal. Steel is ordinarily used. The shell carries the usual asbestos diaphragm 5. This shell 80 in operation forms the cathode. At its top it carries annular top member 6 of special concrete. Resting on this annular member is the top 7 of the anode chamber, this top serving to carry depending anodes 8 of graphite or other usual material. Anode carrier 7 may also be of concrete. It is provided with a domed top. Through this dome enters chlorin outlet pipe 9. The bottom of the annulus 6 is recessed at 10 to take the top 85 of the diaphragm. Peripherally, element 6 is provided with a laterally extending recessed flange 11 adapted to seat against and make a joint with casing 1 by means of a mastic composition 14. The cell is provided 90

with the usual brine feed 12 and gas outlet 13 for hydrogen.

The cell shown may be operated in any of the usual ways. The cathode chamber may 5 contain catholyte or oil.

There is material advantage in supporting the anode and the anode chamber top, as above described, upon the bottom of the cell instead of upon a flanged top. In particular, the arrangement constitutes a simplified construction and permits a gas tight top requiring but little repair and facilitating repair when necessary. When both the bottom of the cathode shell and the top cover 10 member are made of concrete the external insulation between anode and cathode is materially improved. The construction affords a simplified solution of the problem of 15 keeping the cathode hydrogen from mixing 20 with the anode chlorin.

What I claim is:—

1. An electrolytic cell, an open topped casing forming a cathode chamber with an orificed metal shell within the casing and resting 25 on its bottom, said shell serving as a cathode and being laterally spaced from the walls of the casing, a diaphragm in the shell, an interior chamber within the diaphragm, anodes in said interior chamber and a two 30 part cover member for the cell fitting inside the top edges of said casing with a plastic gas tight joint between said member and the casing, said member supporting the anodes and being attached to the cathode shell, the 35 weight of the cathode, diaphragm, cover and anodes resting upon the bottom of the cell.

2. In an electrolytic cell, an open topped cylindrical casing having straight vertical sides, a contained perforated metal cylindrical cathode carrying and enclosing a diaphragm, a bottom member for said cathode supported upon the bottom of the cell and a top circular peripherally flanged cover member for the cell inserted within the cylindrical 40 casing and supported by the cathode and supporting a plurality of anodes within said enclosed diaphragm, both said members being of concrete construction and the flange of said cover member having a recess, with plastic material in the recess making a gas tight joint 45 with the casing.

3. An electrolytic cell comprising an open topped, straight-sided, cylindrical casing forming a cathode chamber with an orificed cylindrical metal shell within the casing and resting on its bottom, said shell serving as a cathode and being laterally spaced from the walls of the casing, a diaphragm in the shell defining an interior chamber within the diaphragm, anodes in said interior chamber and a two-part circular cover member for the cell fitting inside the top edge of said casing with a plastic gas-tight joint between said member and the casing, said member supporting the anodes and being attached to the 50 55 60 65 70 75 80 85 90 95 100 105 110 115 120 125 130

cathode shell, the weight of the cathode, diaphragm, cover and anodes resting upon the bottom of the cell.

In testimony whereof, I have hereunto affixed my signature.

LA FAYETTE D. VORCE.
